J. P. NIKONOW,
COMBINED LIFTING JACK AND HOIST,
APPLICATION FILED SEPT. 22, 1917.

1,295,358.

Patented Feb. 25, 1919.

UNITED STATES PATENT OFFICE.

JOHN P. NIKONOW, OF DAYTON, OHIO.

COMBINED LIFTING-JACK AND HOIST.

1,295,358.

Specification of Letters Patent. Patented Feb. 25, 1919.

Application filed September 22, 1917. Serial No. 192,813.

To all whom it may concern:

Be it known that I, JOHN P. NIKONOW, a citizen of Russia, and a resident of the city of Dayton, in the county of Montgomery and State of Ohio, have invented a new and useful Improvement in Combined Lifting-Jacks and Hoists, of which the following is a specification.

My invention relates to the lifting jacks 10 and hoists combined and has particular reference to the portable, hand or power operated mechanisms, suitable for carrying in automobiles, trucks and the like.

My invention has for its object to provide 15 a mechanism of the character, above indicated, which is simple in form and efficient in operation, the same apparatus being suitable for raising the load above the ground by jacking it up, for moving the load horizontally and for hoisting it by means of a 20 rope or chain.

There have been employed heretofore, separate apparatus for each of the above mentioned operations, lifting jacks being of such 25 construction, as to render them unsuitable for hoisting work.

I have produced a mechanism, which utilizes features of ordinary lifting jacks, and, in addition, has parts, which in combination 30 with the aforesaid features, enable the mechanism to be used as a hoist, winch or capstan.

In the accompanying drawings, Figure 1, is a plan view of my mechanism, when used 35 as a lifting jack. Fig. 2 is an elevation. Fig. 3, shows the same mechanism with additional parts, used as a hoist. Fig. 4 shows the handle with the attachment to change direction of lift.

40 The mechanism comprises a stem or movable rack 1 with ratchet teeth 2 and threaded portion 38. This stem has an enlarged portion or jackhead 3, adapted to engage the load, such as an axle of the vehicle, when 45 raising same from the ground.

The stem 1 slides in the stand 4 with the foot 5, which is sufficiently large to provide a safe resting base, when the mechanism is used as a jack.

50 A handle 6 is pivotally (pivot 6^a) connected to the stand 4. The pawl 7 is connected to the handle on a pivot 8. Another pawl 9 is attached by means of a pivot 10 to the stand 4 and prevents the rack from 55 slipping down, when the handle is released.

An arm 11 is mounted on a pivot 12 and

has a slot 13, in which slides a pin 14, fastened to the pawl 9. Spring 15 tends to move the arm 11 toward the pawl 9, pressing it against the rack. The extension 16 60 fits in the slot 17 in the handle 6, when the latter is lowered.

Another arm 18 on a pivot 19 engages the pawl 7 by means of two flat springs 20, sliding on the pin 21. Spring 22 tends to 65 press the pawl 7 against the ratchet 2 through action of the arm 18 and springs 20. The projection 23 enters freely slot 24 in the handle 6, when the latter is raised.

When the jack is used for lowering the 70 load, the sleeve 25 is shifted toward the pivot on the handle by means of shifting rod 37 thus closing the slots 17 and 24. As a result, when the handle is raised, sleeve 25 strikes the arm 18 and causes disengagement of the pawl 7 and rack 1. With 75 the handle lowered, the pawl 7 engages the rack again. With the further downward movement the sleeve 25 strikes the link 11 and disengages the arm 9 from the rack 2, 80 thus enabling the rack to be lowered by one tooth. It is easy to see, that both pawls cannot be disengaged at the same time, so that when load is not held with the acting pawl 9. 85 7, it will be suspended on the safety pawl 9.

The ears 26 are provided on the stand, so that it can be suspended on the rope or a similar carrier 27 with a hook 28 when it is desired to use the jack as a hoist. A rod 29 is screwed then in the threaded portion 90 38 of the rack 1. This rod has an enlarged portion with automatic clamps 31 on pivots 32 and with springs 33. These clamps allow the rope or suitable carrier 34 to pass freely 95 in one direction and hold it firmly, when direction of the pull is reversed. Similar clamps 35 are attached to the stand 4.

With the load on the end of the rope 34, the jack may be operated in the ordinary way for lifting, the pull of the load causing 100 the clamps 31 to grip the rope. When the rack 1 is raised its full travel, the slack part of the rope is pulled through the clamps 35, and the rack is lowered down, the clamps 35 gripping the rope and the clamps 31 automatically releasing it. The whole mechanism is ready then for another lift. Therefore, the clamps 35 and 31 hold the load 105 alternatively.

In order to facilitate the clamping of the 110 rope, it may be provided with the cord or wire bands 36, as shown on Fig. 3.

Important advantages of the mechanism above described are, that it can raise or lower considerable weights with small movements of the operating handle, can be operated with one hand only, changed from lowering to lifting and vice versa being accomplished from the end of the handle, and that it can also be used as a hoist, for instance, when it is necessary to pull the vehicle from

10 a mud hole.

I claim as my invention:

1. In a jack, the combination, with a stand and a rack bar passing through said stand and having a jack head, of a retaining pawl carried by said stand for engagement with said rack bar, an operating handle pivoted on said stand, and an operating pawl pivoted to said handle and acting on said rack bar, a sleeve surrounding a portion of said handle, and means for sliding said sleeve along said handle, with connections whereby said sliding movement of said sleeve reverses the direction of movement of said rack bar.
2. In a jack, the combination, with a stand and a rack bar passing through said stand, of a retaining pawl carried by said stand and engaging said rack bar, an operating handle pivoted on said stand, an operating pawl carried by said handle, and engaging said rack bar, arms pivoted to said stand and

having sliding connections with said operating and said retaining pawls, respectively, and a sleeve slidably carried by said handle, the construction being such that the sleeve 35 when in one position will cause alternate operations of said arms, whereby to disengage the pawls successively from said rack bar.

3. In a jack, the combination, with a stand and a rack bar passing through said stand, 40 an operating handle pivoted to said stand, operating and retaining pawls engaging said rack bar, the retaining pawl being pivoted on said stand and the operating pawl on said handle, arms pivoted on said stand and having sliding connections with the operating and the retaining pawls, respectively, springs tending to engage both said pawls with said rack bar, and a sleeve carried 45 slidably on said handle, constructed when 50 in one position to release said pawls alternately and move them against the tension of said springs to withdraw said pawls alternately from said rack bar.

In testimony whereof I have hereunto subscribed my name this fifteenth day of September, 1917.

JOHN P. NIKONOW.

Witnesses:

H. N. RIEHLE,
H. J. LINKERT.
